CLAIM

The ornamental design for a toilet seat for children, as shown and described.

DESCRIPTION

FIG. 1 is a perspective view of a toilet seat for children showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a bottom side perspective view thereof.

Any shading and cross-hatching are not features of the design but are utilized to illustrate the surface contours of the toilet seat for children design in the drawings.

The broken lines in the drawings depict portions of the toilet seat for children that form no part of the claimed design.
